E. F. HATHAWAY

YARN SPOOL

Filed Oct. 5, 1923

Inventor:
Edgar F. Hathaway
by Geo. N. Goddard, Atty.

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

YARN SPOOL.

Application filed October 5, 1923. Serial No. 666,837.

To all whom it may concern:

Be it known that I, EDGAR F. HATHAWAY, a citizen of the United States, and resident of Wellesley, in the county of Norfolk and State of Massachusetts, have invented certain new and useful Improvements in Yarn Spools, of which the following is a specification.

This invention relates to yarn spools especially of the type used for carrying the yarn in tube frames that are employed in tuft weaving, and is intended to provide a simple and conveniently operated construction for the spool journal so that the spool 10 may be mounted in closed bearings formed in the bearing brackets carried by the tube frame or other support so as to readily permit the retracting of the journal preparatory to removing the spool.

20 To this end the invention comprises, generally speaking, a journal construction characterized by an axially movable journal pin mounted in the end of the spool and normally projecting beyond the head or end 25 of the spool to rest in its bearing, combined with retracting means located between the spool and the bearing bracket so as to be readily accessible to the attendant when he has occasion to remove the spool from its 30 bearing. These and other features of the invention will be described in the following specification and will be defined in the claims hereto annexed.

In the accompanying drawings I have illustrated one form of construction embodying the principles of this invention, in which:

Figure 1 is a front elevation showing one 40 end of the spool mounted in a well known type of tube frame.

Figure 2 is a horizontal central section through the spool and the adjacent part of its supporting bracket showing the interior parts of the journal construction.

45 Figure 3 is an end elevation showing the relation of the bearing bracket to the spool end and journal.

In the present instance I have shown a 50 spool whose barrel 1, is of metallic tubing to whose end is secured a metallic flanged disk or head 2, forming a cover for the open end of the tubular barrel.

Concentrically with the spool I mount an

axial hollow casing 3, which is securely fastened to the head of the spool so as to hold 55 it firmly in place.

Inside this hollow inwardly projecting casing 3, is mounted a slidable or telescoping sleeve 4, which has bearing against the interior wall of said casing to allow the 60 sleeve to slide in and out. The sleeve is provided with a transversely or radially projecting disk 5, which preferably is of greater width than the upper portion of the bearing bracket *c*, of the tube frame in 65 which the spool is mounted to permit unwinding of the yarn thereof.

In this instance an elongated axial pin 6, is preferably provided with a head 7, at one end to limit its outward movement by 70 contact with the inner end of the hollow casing 3. The outer end of the pin passes through the sleeve 4 and the disk 5, so as to project some distance beyond the disk to 75 permit it to lie in the bearing opening of the bearing bracket. The sleeve with its disk flange 5 is secured to the journal pin 6, in any suitable manner as by a transverse fastening pin 9. A helical spring 8, coiled around the journal pin, is seated against the 80 inmost wall of the casing 3 and exerts an outward thrust against the flange sleeve, thereby tending to yieldingly force outward both the pin and its guide sleeve, the flange 5 being located preferably far enough from the outer end of the journal pin to avoid 85 contact with the bearing bracket when thrust outward to normal operative position.

It will be seen that with the arrangement described the disk is readily accessible 90 around the greater part of the upper end of the bearing bracket so that it can be pressed inward by the finger of the attendant, thereby serving as a retracting member for withdrawing the journal pin entirely 95 out of the bearing opening in the bearing bracket *c*, thus permitting the spool to be lifted bodily out of the tube frame.

This construction enables the bearing brackets which support the spool above the carrier bar *a*, to be made with closed bearing perforations from which the spool can be readily removed by the retraction of one of the journals without the use of any special appliance or tool.

Heretofore it has been customary to use

a plunger type of supporting journal for the spool and in conjunction therewith a closed bearing opening in the spool-supporting bracket. With such construction the attendant usually had to carry some special tool for forcing the journal inward by end pressure thereon until it cleared the bearing bracket, and as the suspension hanger arms lay very close across the end of the 10 spool journal this was a rather bothersome and inconvenient operation.

By the present construction no special tool is required, and the operator by merely pressing inwardly on the flange or disk 5, 15 easily withdraws the journal from engagement with the bearing bracket to allow it to completely clear the bearing bracket in the act of removing, one finger of the hand to grasp the spool to pull it out being sufficient to retract the journal pin.

The tube frame, as shown in Figure 1, is of well known type of construction and embodies the longitudinal tube-carrying bar *a* and the suspension hanger *b* from which 25 projects upwardly and inwardly the spool bearing bracket *c*.

What I claim is:

1. A yarn spool embracing in its construction, a yarn-receiving barrel, an end head 30 secured thereto, an axially movable journal concentrically mounted in the spool and provided near its projecting end with a lateral projection arranged outside of the head to be accessible for retracting the 35 journal from its external bearing, substantially as described.

2. A yarn-spool for a tube frame or the like, embracing in combination a spool head and barrel, and a spring-pressed outwardly 40 projecting journal mounted axially of the spool and provided near its outer end with means by which the journal may be retracted axially from its bearing to permit the removal of the spool, substantially as 45 described.

3. A yarn spool for a tube frame or the like, embracing in its construction a spool head and barrel, a retractile journal yieldingly pushed outward for engagement with 50 its bearing, and retracting means connected with the journal and projecting laterally beyond the periphery of the bearing member in position accessible to the attendant, whereby the journal may be conveniently 55 withdrawn from the bearing to permit the

removal of the spool, substantially as described.

4. A journal construction for a yarn spool embracing an axial journal pin mounted in the end of the spool, a spring 60 acting to normally press the journal pin outward to operative bearing position, a collar secured on said pin to project laterally from the pin adjacent to a pin-supporting bearing member, and means limiting the 65 outward movement of the pin, substantially as described.

5. A yarn spool provided at its end with an axial bore, an axially movable journal pin mounted therein, a radially flanged 70 sleeve secured to the pin affording a guiding bearing with the bore of the spool, a compressed spring surrounding the pin and thrusting outwardly against said sleeve, and means for limiting the outward endwise 75 movement of said pin and its sleeve, substantially as described.

6. In a yarn spool the combination of a tubular metallic barrel, a circular metallic head secured thereto so as to cover the 80 open end of the tubular barrel, a tubular casing secured centrally of the head to project axially inside the barrel, a flanged sleeve mounted to slide axially in the casing, a journal pin movably axially and having 85 guiding support in the inner end of the casing and secured in the sleeve, and a spring acting normally to press the journal pin outwardly into a supporting bearing, substantially as described.

7. A journal construction for a yarn spool, embracing a journal pin mounted to telescope into the end portion of the spool, a helical spring acting to thrust said journal pin outwardly beyond the head of the spool, 95 and a transversely disposed retracting disk connected with the pin beyond the head of the spool, substantially as described.

8. The combination of a yarn spool comprising a barrel and head, an external bearing bracket, an axial journal slidably mounted in the spool to enter the bearing bracket, and journal-retracting means located between the spool head and the bearing member and connected with the 100 spool journal, substantially as described.

In witness whereof, I have subscribed the above specification.

EDGAR F. HATHAWAY.
